UNITED STATES PATENT OFFICE.

THOMAS J. MURPHY, OF ROCHESTER, NEW YORK, ASSIGNOR OF ONE-HALF TO JAMES P. DUFFY, OF ROCHESTER, NEW YORK.

STOP MECHANISM FOR SOUND-REPRODUCING APPARATUS.

1,359,728.

Specification of Letters Patent. Patented Nov. 23, 1920.

Application filed September 17, 1917. Serial No. 191,735.

To all whom it may concern:

Be it known that I, THOMAS J. MURPHY, of Rochester, in the county of Monroe and State of New York, have invented certain new and useful Improvements in Stop Mechanism for Sound-Reproducing Apparatus; and I do hereby declare the following to be a full, clear, and exact description of the same, reference being had to the accompanying drawings, forming part of this specification, and to the reference characters marked thereon.

The purpose of my invention is to afford improvements in electrically driven sound reproducing machines whereby to simplify the control of the machine and make it easier for the operator to properly position the needle and tone arm so as to obtain accurate functioning with a record. In a more specific aspect, the object of the improvement is to provide a switch for governing the circuit of the motor that drives the machine, having the switch under automatic regulation to open the motor circuit at any predetermined point during the travel of the tone arm across the record. A further purpose of the invention is to provide a lamp in the circuit which is located so as to illuminate the record and facilitate positioning the tone arm, and govern the lamp by the same switch which controls the motor circuit, in a manner that makes it possible to furnish current to the lamp independently of the motor and while the latter is out of operation. An additional object is to provide an improved style of mounting for the motor and for the governor which controls the speed of the turn table. To these and other ends the invention consists in certain improvements and combinations of parts, all as will be hereinafter more fully described, the novel features being pointed out in the claims at the end of the specification.

In the drawings:

Fig. 1 is a plan view showing the application of the invention to a flat record type of sound reproducing machine;

Fig. 2 is a bottom plan view of the motor board;

Fig. 3 is a side elevation showing the switch and coöperating parts in section;

Fig. 4 is a plan view of the switch in the position which it assumes with the motor running;

Fig. 5 is a diagrammatic view showing the

arrangement of circuits and with the switch in the same position as in Fig. 4;

Fig. 6 is a similar diagrammatic view of a slightly modified form of controlling circuits, and

Fig. 7 is a detail view in side elevation of the centrifugal governor mounting.

Similar reference characters throughout the several views indicate the same parts.

The structure comprises a swinging tone arm 1 which carries a sound box 2, and 3 is the turn table upon which the record 4 is arranged. The turn table is driven by a friction pulley 5 arranged upon the armature shaft of a motor 6 which is electrically driven. The motor 6 is pivotally disposed between arms 7, as shown in Fig. 2, where 7^a designates felt bushings supporting the pins 7^b, carried by the motor frame. The felt bushings 7^a rest against shoulders 7^c on the arms, and are held in place by heads 7^d on the pins. 7^e are fiber washers positioned between the heads 7^d and the felt bushings. There is sufficient clearance between the shoulders 7^c and the pins 7^b to prevent the latter from ever contacting with the shoulders, and thus the motor rests entirely on the felt bushings, thereby preventing any vibration or hum of the motor from being transmitted to or taken up by the metal or wooden parts which support it. The pulley 5 is held yieldingly against the turn table by adjustable spring means. To this end I employ a stationary abutment 9, through which passes a rod 9^a pivotally connected by a yoke 9^b with the end 10 of the motor frame. Expansion springs 9^c and 9^d are located around the rod, on opposite sides of abutment 9, the first mentioned one actuating the motor frame toward the driven member, while the latter 9^e spring 9^d is adjustable by a nut 9^e, to vary the tension exerted upon the motor frame. Felt washers 9^f are positioned upon the rod 9^a against the abutment 9, and metal washers 9^g are arranged between the felt washers and the metal springs. The centrifugal governor is similarly mounted, the governor shaft being designated by 11 and journaled in a holder 12 which is pivotally mounted between the stationary arms 13. 14 and 14^a are expansion springs located on opposite sides of the stationary abutment 15 and surrounding a rod which carries a yoke 14^b pivoted to the end of the shaft frame 12. The governor may be of any desirable form, and

is driven from the pulley 16 shown in dotted lines Fig. 1 in frictional engagement with the turn table.

Referring to Fig. 5, the motor 6 is connected at one side with the line conductor 17 and from the other side, a conductor 18 leads to a contact 19. The latter engages a separable contact 20 which in turn is connected to the other side 21 of the main line 10 to which current may be supplied from any source of energy. The main line conductor 17 also leads to a contact 22 which is normally in spaced relation to a contact 23, the latter being electrically connected to the 15 aforesaid contact 19. 24 designates the switch, which in the position shown in Fig. 5, is entirely removed from the several contacts permitting them to assume their normal position with contacts 19 and 20 engaged 20 and contacts 22 and 23 disengaged. The switch 24 is mounted on an arm 25 and is held in the position shown in Fig. 5 by an adjustable stop or plate 26 which is carried by the tone arm. The plate 26 is slideable in 25 grooves or ways in a holder 27 on the tone arm and fits said grooves closely enough to be frictionally retained in adjusted position therein, and is provided with a recess or opening 28 into which the switch arm 25 30 moves when the tone arm reaches a predetermined position on the record. In the operation of this part of the mechanism, the tone arm is set at the end of the playing position upon the record, and the stop 26 35 is then adjusted until the arm 25 engages the recess 28. This determines the position of adjustment for the stop 26. The switch arm 25 is then withdrawn from the recess 28 as will be described more fully in a moment, and the tone arm and stop are then moved over to the initial playing position from 40 which the record starts to travel. The parts are then in the position indicated by Fig. 5, and current is supplied to the motor 6 from conductor 21 through contacts 20 and 45 19 successively, thence by conductor 18 to the motor and back to the other line conductor 17. The motor continues in operation until the tone arm has traveled far enough 50 to permit the switch arm 25 to move into the recess 28, whereupon the switch engages the contact 20 and moves it away from contact 19, breaking the circuit at this point and thus stopping the motor.

55 The switch structure is indicated more fully in Figs. 3 and 4. The switch arm 25 is actuated by a spring 29 which is disposed in the housing 30, and arranged between a wall of the housing and a pin 31 on the 60 switch arm. The pin carries a finger piece 32 by which it is movable back and forth, and 33 is a pivoted catch which engages the end of the pin 31 and holds the switch arm in retracted position for a purpose that will 65 appear presently. The catch 33 is arranged

upon an arbor 34 having a finger piece 35 at its outer end as shown in Fig. 4.

Arranged in series with the main line circuit is a lamp 36 which is preferably positioned at a point in proximity to the 70 turn table as shown in Fig. 1, and adapted when lighted to illuminate the surface of the record and thereby facilitate initially positioning the tone arm. With the arrangement illustrated in Fig. 5, the lamp 75 36 is always energized while the motor is energized, and when the contacts 19 and 20 are separated by the release of the switch, the lamp 36 is deenergized by the opening 80 of the main circuit.

Before the motor is started it is desirable to close the lamp circuit to have a light upon the record, and to this end the switch is retracted, and held in such position by the catch 33, thereby bringing the contacts 22 85 and 23 into engagement with one another. The lamp is thus lighted by current passing from the conductor 21 through contacts 20, 19, 23 and 22, thence through conductor 17 and to the lamp, while the motor is short 90 circuited. When the parts are ready for the playing operation, the finger piece 35 is turned to release the switch arm which then assumes the intermediate position shown in Fig. 5 during the playing operation. In addition to affording a desirable light close to the record, the lamp 36 also provides a resistance in the motor circuit which is of considerable advantage in 95 steadyng the speed of the motor and thus assisting in maintaining regularity of motion of the turn table and record. A supplemental circuit 37 and hand switch 38 may be employed for closing the lamp circuit independently of the controlling switch 105 already described.

In the modified form illustrated in Fig. 6 the motor is bridged directly across between the main line conductors while the contacts 39 and 40, also 41 and 42 are separated in the normal or playing position. When the switch arm moves in either direction from the position shown in Fig. 6, one or the other pair of contacts are brought into engagement with one another and the 110 circuit closed at this point, thereby short circuiting the motor, but maintaining current through the lamp. Otherwise the operation is the same as that already described. 43 is a supplemental 115 switch arranged in the main line conductor 21 for opening the main circuit independently of the automatic switch already described.

The operation of my device is as follows: 125 the tone arm is moved to the position it occupies at the end of the record, and the plate 26 is adjusted with its opening in position to register with the pin 25. The pin 25 is then retracted and the tone arm moved to 130

starting position. In the operation of the machine, when the tone arm moves to the end of the record the spring 29 moves the pin 25 into the opening 28 and moves the contact 20 away from the contact 19 and breaks the circuit and automatically stops the motor.

I claim as my invention:

1. In a sound reproducing apparatus, the combination of a turn table, an electric motor for operating said table, a tone arm movable over said table, an electric lamp located in proximity to said table to illuminate the same, electrical connections between said motor and lamp and a source of power, a switch governing said connections and movable to a plurality of positions in one of which the motor circuit is open and in another of which the lamp circuit is closed, and actuating means controlled by said tone arm for moving said switch to said position for opening the motor circuit.

2. In a sound reproducing apparatus, the combination of a turn table, an electric motor connected with a source of power for operating said table, a lamp connected with said source of power in series with said motor for illuminating said table, connections for short circuiting said motor, a switch movable selectively from an intermediate operating position to position for opening the motor circuit or to position for shortcircuiting the motor, a tone arm movable across said table and actuating means controlled by said tone arm for moving said switch to position for opening the motor circuit.

3. In a sound reproducing apparatus, the combination with a turn table and an electric motor for operating it, of electrical connections including said motor, a tone arm movable over the turn table, an electric lamp located in proximity to said turn table to illuminate the same and also included in said connections, a switch movable to a plurality of positions in one of which the motor circuit is opened and in the other of which positions the lamp circuit is closed, actuating means for moving said switch to position for opening the motor circuit, retaining means for said switch counteracting said actuating means, and an adjustable stop on the tone arm coöperating with said switch and acting to release it from said retaining means at a predetermined point on a record to open the motor circuit.

4. In a sound reproducing apparatus, the combination with a turn table and an electric motor for operating it, of electrical connections including said motor, a tone arm mov-

able over the turn table, an electric lamp located in proximity to the turn table to illuminate the same and also included in said connections, and a switch controlled by said tone arm and movable to one position in which the motor circuit is closed and to another position in which the lamp circuit is closed while the motor circuit is short-circuited.

5. In a sound reproducing apparatus, the combination with a turn table and an electric motor for operating it, of electrical connections including said motor, a tone arm movable over the turn table, an electric lamp located in proximity to said turn table to illuminate the same and also included in said connections, a switch movable to one position in which the motor circuit is open and to another position in which the lamp circuit is closed while the motor circuit is short-circuited, actuating means for moving said switch to position for opening said motor circuit and an adjustable stop on the tone arm coöperating with said switch and acting to release it at a predetermined point on a record to open the motor circuit.

6. In a sound reproducing apparatus, the combination with a turn table and an electric motor for operating it, of electrical connections including said motor, an electric lamp located in proximity to said turn table to illuminate the same and also included in said connections, a switch movable to one position in which the motor circuit is closed and to another position in which the lamp circuit is closed while the motor circuit is shortcircuited, actuating means for moving said switch to said first position, and a locking device acting to hold the switch in the last named position.

7. In a sound reproducing apparatus, the combination with a turn table and an electric motor for operating it, of electrical connections including said motor, a tone arm movable over the turn table, an electric lamp located in proximity to said turn table also governed by said circuit, a switch movable to one position in which the motor circuit is open and to a second position in which the motor circuit is closed and also to a third position in which the lamp circuit is closed while the motor circuit is short-circuited, a manually operable locking device acting to hold the switch in said third position, and an adjustable stop controlled by said tone arm and coöperating with said switch and acting to release it at a predetermined point on a record to open the motor circuit.

THOMAS J. MURPHY.
